UNITED STATES PATENT OFFICE.

FRED H. KRUPP, OF NORTHFIELD, MINNESOTA, ASSIGNOR OF TWO-FIFTHS TO BURTON C. SWENSON, OF NEW LONDON, MINNESOTA.

RAIL-FASTENER FOR METAL TIES.

1,241,224.

Specification of Letters Patent. Patented Sept. 25, 1917.

Application filed February 21, 1917. Serial No. 150,222.

To all whom it may concern:

Be it known that I, FRED H. KRUPP, a citizen of the United States, residing at Northfield, in the county of Rice and State 5 of Minnesota, have invented certain new and useful Improvements in Rail-Fasteners for Metal Ties; and he does hereby declare the following to be a full, clear, and exact description of the invention, such as will 10 enable others skilled in the art to which it appertains to make and use the same.

My invention has for its object to provide an extremely simple and highly efficient rail fastener for metal railway ties; and, to this 15 end, it consists of the novel devices and combinations of devices hereinafter described and defined in the claims.

In the accompanying drawings, which illustrate the invention, like characters indicate like parts throughout the several views. 20

Referring to the drawings:

Figure 1 is a fragmentary view showing in transverse section, one of the rails of a railway track secured to a metal tie by 25 means of two of the improved fasteners;

Fig. 2 is a fragmentary view principally in side elevation with some parts broken away and some parts sectioned;

Fig. 3 is a plan view of the parts shown 30 in Fig. 1;

Fig. 4 is a longitudinal section taken on the irregular line 4—4 of Fig. 1; and

Fig. 5 is a fragmentary plan view of the metal tie.

The numeral 6 indicates a metal railway tie of the I-beam type and having supported 35 on its top horizontal flange one of the rails 7 of a railway track. Formed in the top horizontal flange of the tie 6 and underly-

ing each longitudinal edge of the base flange of the rail 7 is a pair of elongated apertures 8. These apertures 8 extend parallel 40 with the web of the tie 6 and are located, one on each side of said web with their inner sides flush therewith. It is important to note that the longitudinal edges of the base flange of the rail 7 intersect the apertures 8 at their intermediate portions.

Formed in the web of the tie 6, in substantially the same vertical plane with each pair 45 of apertures 8, is an aperture 9. These apertures 9 are inclined upwardly and away from each other, as best shown in Fig. 1. The rail 7 is secured to the tie 6 by a pair

of spikes 10 inserted, each through one of 55 the apertures 8 of each pair thereof and with their heads engaging the opposite longitudinal edge portions of said rail. The bodies of the spikes 10 extend through rectangular links 11, and one of these links 60 11 is mounted in each aperture 9 with freedom for endwise sliding movement transversely of the tie 6 and for bodily movement longitudinally thereof. By reference to Fig. 2, it will be noted that one side of 65 the spike 10 is straight and bears directly against the web of the tie 6 and the other side thereof is upwardly tapered and bears directly against the adjacent end of the link 11, which is correspondingly beveled. The 70 two spikes 10 are placed in diagonally opposite apertures, so as to always bring their straight sides in direct contact with the web of the tie 6.

A wedge 12 is inserted through the other 75 aperture 8 of each pair and through the respective link 11. The straight sides of the wedges 12 bear directly against opposite sides of the web of the tie 6 from the spikes 10 and their other sides are beveled downwardly. The inner faces of the adjacent 80 ends of the links 11 are beveled in the same direction as the outer sides of the wedges 12, and have direct engagement therewith. Obviously, by driving the wedges 12 into 85 the links 11, said links are moved lengthwise into direct frictional contact with the spikes 11. The beveled surfaces of the links 11, which engage the upwardly tapered surfaces of the spikes 10, tend to draw said 90 spikes downward and, at the same time, prevent the same from working upward. It will thus be seen that the heads of the spikes 10, engaging the base flange of the rail 7, hold said rail firmly in position on the tie 6. 95

To prevent the wedges 12 from working loose under the vibration of the rail 7 and tie 6, a flat key 13, having a laterally bent end, is provided therefor. The bodies of the keys 13 extend between the wedges 12 and 100 web of the tie 6, with their laterally bent ends extending into the apertures 9, over the links 11, to thereby anchor said keys. After the wedges 12 are driven to place, the upwardly projecting ends of the keys 13 are 105 upset over the tops thereof. It is, of course, understood that the keys 13 may be anchored in various different ways.

The rail 7 is secured to the tie 6 by a pair

From the above description, it is evident that the rail 7 may be set to the proper gage of the track by adjusting the links 11 in the apertures 9. It is also evident that each pair of links 11 may be set different distances apart to properly space the spikes 10, in order that they may engage the base flanges of rails of different weights, and hence having base flanges which vary in width.

10 Outward lateral pressure on the rail 7, acting through the spikes 10 as levers, will tend to twist the links 11 in horizontal planes and thereby cause the same to frictionally engage the upper and lower surfaces of the apertures 9. This twisting of the links 11 will securely hold the same against lateral sliding movement in the apertures 9 away from the rail 7. The upwardly inclined surfaces of the apertures 9 will also greatly assist in preventing the links 11 from moving away from the rail 7, while at the same time they will tend to cause said links to move toward each other and hence keep the heads of the spikes 10 in overlapping engagement with the base flange of the rail 7. By reference to the drawings it will be noted that the improved fastener will permit shims to be inserted between the rail and tie which is of course highly important.

30 What I claim is:

1. The combination with a tie having a vertical web, and a rail supported on said tie, of a link seated in an aperture in the web of the tie with freedom for endwise movement longitudinally of the rail, a spike having its body extending into said link and its head engaging the base flange of the rail, and a wedge inserted into said link on the opposite side of the web of the tie from the spike for holding the link in engagement with the spike.

2. The combination with a tie having a vertical web, and a rail supported on said tie, of a link seated in an aperture in the web of the tie with freedom for endwise movement longitudinally of the rail, a spike having its body extending into said link and its head engaging the base flange of the rail, a wedge inserted into said link on the opposite side of the web of the tie from the spike for holding the link in engagement with the spike and a key for holding the wedge against lifting movement.

50 3. The combination with a tie having a

vertical web, and a rail supported on said tie, of a link seated in an aperture in the web of the tie with freedom for endwise movement longitudinally of the rail, a spike having an upwardly tapered body extending into said link and its head engaging the base flange of the rail, and a wedge inserted into said link on the opposite side of the web of the tie from the spike.

4. The combination with a tie having a vertical web, and a rail supported on said tie, of a link seated in an aperture in the web of the tie with freedom for endwise movement longitudinally of the rail, a spike having an upwardly tapered body extending into said link and its head engaging the base flange of the rail, and a wedge inserted into said link on the opposite side of the web of the tie from the spike, the inner walls of the ends of the link being beveled to engage the correspondingly formed engaging surfaces of the bodies of the spike and wedge.

5. The combination with a tie having a vertical web, and a rail supported on said tie, of a link seated in an aperture in the web of the tie with freedom for endwise movement longitudinally of the rail and for bodily movement transversely thereof, a spike having an upwardly tapered body extending into said link and its head engaging the base flange of the rail, and a wedge inserted into said link on the opposite side of the web of the tie from the spike.

6. The combination with a metal tie and a rail supported thereon, said tie having a vertical web with two upwardly inclined apertures, located one under each of the longitudinal edges of the rail, a link mounted in each of said apertures with freedom for endwise movement longitudinally of the rail and for bodily movement transversely thereof, spikes having upwardly tapered bodies extending into said links and their heads engaging the base flange of the rail, and wedges inserted into said links on the opposite side of the web of the tie from the spikes.

In testimony whereof I affix my signature in presence of two witnesses.

FRED H. KRUPP.
